REEL FOR TAPE OR THE LIKE

Horace T. Montgomery, Mission Viejo, and Hormoz Rafaat, Corona del Mar, Calif., assignors to Memorex Corporation, Santa Clara, Calif.

Filed June 11, 1971, Ser. No. 152,472

Term of patent 14 years

Int. Cl. D14—01; D16—03

U.S. Cl. D26—14 B

FIG. 1

FIG. 3

FIG. 1 is a front elevational view of a reel for tape or the like, embodying our new design;

FIG. 2 is a bottom plan view thereof taken from the bottom of FIG. 1; and

FIG. 3 is a rear elevational view thereof.

We claim:

The ornamental design for a reel for tape or the like, substantially as shown.
